US0D1001731S

(12) **United States Design Patent** (10) **Patent No.:** **US D1,001,731 S**
(45) **Date of Patent:** **** Oct. 17, 2023**

(54) **CHARGING CASE FOR EARPHONES**

(71) Applicant: **BEIJING XIAOMI MOBILE SOFTWARE CO., LTD.**, Beijing (CN)

(72) Inventors: **Qing Li**, Beijing (CN); **Keliang Xun**, Beijing (CN); **Weiwei Chen**, Beijing (CN); **Chong Wang**, Beijing (CN); **Zhiyao Wang**, Beijing (CN)

(73) Assignee: **BEIJING XIAOMI MOBILE SOFTWARE CO., LTD.**, Beijing (CN)

(**) Term: **15 Years**

(21) Appl. No.: **35/513,412**

(22) Filed: **Sep. 16, 2021**

(80) **Hague Agreement Data**

Int. Filing Date: **Sep. 16, 2021**

Int. Reg. No.: **DM/218167**

Int. Reg. Date: **Sep. 16, 2021**

Int. Reg. Pub. Date: **Jan. 21, 2022**

(30) **Foreign Application Priority Data**

Mar. 16, 2021 (CN) 202130141895.1

(51) **LOC (14) Cl.** **13-02**

(52) **U.S. Cl.**

USPC **D13/108; D3/294**

(58) **Field of Classification Search**

(57) **CLAIM**

The ornamental design for a charging case for earphones, as shown and described.

DESCRIPTION

- 1.1** : Front
1.2 : Back
1.3 : Left
1.4 : Right
1.5 : Top
1.6 : Bottom
1.7 : Perspective
1.8 : Perspective
1.9 : Front view of state of change
1.10 : Back view of state of change
1.11 : Left view of state of change
1.12 : Right view of state of change
1.13 : Top view of state of change
1.14 : Bottom view of state of change
1.15 : Perspective view **1** of state of change
1.16 : Perspective view **2** of state of change

(Continued)

The earphone receiving recesses and the recesses on the lid in reproductions **1.9**, **1.11-1.13** and **1.15**, from the outlined edge inward (but excluding the contour edge), form no part of the claimed design.

1 Claim, 14 Drawing Sheets

(58) Field of Classification Search

CPC A45C 2011/001; H04R 1/1025; H02J 7/0003; B65D 43/16
